TRANSPARENT FACED MEDICINE CABINET

Oliver Elliott, Wichita, Kans., assignor to Life Guard, Inc., Denver, Colo., a corporation of Colorado

Filed Nov. 1, 1961, Ser. No. 67,344

Term of patent 14 years

(Cl. D4—3)

FIG. 1 is a front perspective view of a transparent faced medicine cabinet embodying my new design. The opposite side not shown is substantially like the side shown in FIG. 1. The rear is substantially plain, opaque and flat; and

FIG. 2 is a vertical sectional view thereof taken on the line 2—2 of FIG. 1.

The dominant features of my design reside in the portions shown in full lines.

I claim:

The ornamental design for a transparent faced medicine cabinet, substantially as shown and described.
